[57] CLAIM

The ornamental design for a vehicle running board,
substantially as shown.

DESCRIPTION

FIG. 1 is a perspective view of a vehicle running board showing my new design in association with a vehicle which has been shown fragmentarily in broken lines for illustrative purposes only;

FIG. 2 is an enlarged top plan view thereof;

FIG. 3 is an enlarged front elevational view thereof;
FIG. 4 is an enlarged elevational view thereof taken along the left side in FIG. 2;

FIG. 5 is an enlarged elevational view thereof taken along the right side in FIG. 2;

FIG. 6 is an enlarged rear elevational view thereof; and
FIG. 7 is an enlarged bottom plan view thereof.
